ELECTRIC LAMP

Hermann Krefit, Berlin-Friedrichshagen, Willy Wilde, Berlin-Zehlendorf, and Kurt Larche, Berlin-Tempelhof, Germany, assignors to General Electric Company, a corporation of New York

Application April 15, 1938, Serial No. 202,310
In Germany April 20, 1937

3 Claims. (Cl. 176—1.1)

The present invention relates to electric lamps and more particularly the invention relates to such lamps of the type comprising a sealed envelope having mounted therein a gaseous electric discharge lamp device and a ballast resistance connected in series with said discharge device.

In such devices the resistance is mounted in the space between the lamp container and the envelope and is in the form of a filament capable of being heated to incandescence by current flow therethrough during the operation of the discharge device to supplement and complement the light emitted by said discharge lamp device. This is particularly desirable when the gaseous electric discharge lamp device contains a quantity of mercury the vapor of which is excited to luminescence during the operation of the device since the light emitted by the filament is rich in red rays which complement the light emitted by the discharge device which is deficient in such rays. When the discharge device is of the high pressure mercury vapor discharge type it has been found necessary heretofore, in order to obtain a spectrally balanced light, to design the lamp in such manner that more than 50% of the line voltage is dissipated in the series ballast resistance since the light output of the discharge device is from two to four times that of the filament on the same current consumption. Such a resistance is, of course, larger than that required for the purpose of limiting current flow in the discharge device. A fundamental fault with lamps of this type is that the voltage available for the discharge device does not permit operation of the device at its maximum efficiency.

The object of the present invention is to provide an electric lamp of the above type which operates at a higher efficiency and which emits light having a better spectral balance than that emitted by prior lamps. Still further objects and advantages attaching to the device and to its use and operation will be apparent to those skilled in the art from the following particular description.

The invention attains its objects by mounting in the envelope of the lamp an auxiliary filament connected across the terminals of the electric lamp in parallel with the discharge device and the filament which serves as the series ballast resistance for said device. The various elements of the electric lamp of the present invention can be so designed with respect to each other that each element can serve its function at maximum efficiency, for example, the discharge device can be designed to operate at maximum efficiency on a given line voltage without regard to the light out-

put of the series filament. While the series filament does not emit, in such a case, sufficient light to balance the light emitted by the discharge device the auxiliary filament connected across the terminals of the lamp can be so designed that it supplies the required supplementary light during the operation of the lamp and operates at the most favorable temperature.

A particularly advantageous feature of the new electric lamp is its emission of light from the auxiliary filament immediately on the application of potential to the lamp. The heat emitted by the auxiliary filament rapidly raises the container of the discharge device to its operating temperature to shorten the starting period of said device.

In the drawing accompanying and forming part of this specification an embodiment of the invention is shown in a front elevational view.

Referring to the drawing the electric lamp device comprises a sealed envelope or bulb 12 having a high pressure mercury vapor discharge device mounted therein. The tubular container 1 of the discharge device consists of quartz or other vitreous material capable of transmitting visible and ultra violet light and having a high softening temperature. Said container 1 has two electrodes 7 and 8 sealed therein, one at each end thereof, and an auxiliary starting electrode 9 mounted adjacent the main electrode 8. Said electrodes 7 and 8 are thermionic, activated electrodes and are heated to an arc discharge supporting temperature during the operation of the device by the discharge incident thereat. The discharge device has a starting gas therein, such as neon, argon or the like, at a pressure of about 1 to 10 mm. and a body of mercury in such amount that it is wholly vaporized during the operation of the device. Preferably the dimensions and the current load of the discharge device are such so that the vapor is at a pressure of more than 1 atmosphere and, preferably, in the order of 10 atmospheres during the operation of the device. The container 1 has two perforated septums 10 and 11 therein which serve to guide the constricted arc discharge between said electrodes 7 and 8 during the operation of the device.

Said container 1 is supported in said bulb 12 by metal bands 2 and 3 fastened to and insulated from the current leads 4 and 5 of the helically coiled filament 6. Preferably the bulb 12 consists of a visible and ultra violet light transmitting glass and has an inert gas, such as nitrogen, therein. Two current leads 15 and 16 are

fused into the press 14 of the flared stem 13 of the bulb 12. One end of the lead 15 is connected to the current lead 4 and the other end thereof is connected to the contact 17 of the base 17, 5 20 of the bulb 12. One end of the lead 16 is connected to the main electrode 8 by the band 2 and the lead 19 and the other end thereof is connected to the sleeve 20 of the base 17, 20. The auxiliary, starting electrode 9 is connected to 10 the main electrode 7 through a high ohmic resistance 21, and leads 22, 5 and 23.

When potential is applied to the lamp current flows from the contact 17, through leads 15 and 4 to the filament 6, which serves as the ballast 15 resistance for the gaseous electric discharge device, and to lead 5. During starting current flows from the lead 5 over lead 22 through resistance 21 across the gap between auxiliary electrode 9 and the main electrode 8 and thence over the conductors 19, 2, 18 and 16 to the sleeve 20. When the auxiliary, starting discharge between the electrodes 8 and 9 has ionized the gas in the container 1 the main discharge between electrodes 7 and 8 starts and current flows from lead 5 over lead 23 25 across the gap between the main electrodes 7 and 8 through the conductors 19, 2, 18 and 16 to the sleeve 20.

In order to avoid overloading of the series filament 6 during the starting of the gaseous electric 30 discharge lamp device a high ohmic resistance connected in series with said filament 6 and which is short circuited by a bimetallic switch or a resistance having a negative coefficient of electrical resistance, such as a uranium dioxide resistance, when the discharge device is operating at 35 equilibrium is used, when desired. An arrangement of this type is disclosed in copending application Serial Number 136,447, filed April 12, 1937. When desired, part of the filament 6 is short circuited by the switching or resistance means disclosed above during the operation of the lamp as 40 disclosed in the Patent Number 2,020,737, issued November 12, 1935.

An auxiliary incandescent filament 24 supported by wires 25 is mounted in said bulb 12 above said filament 6 and concentric with the container 1 of the gaseous electric discharge lamp device. Said filament 24 is connected to the contacts 17 and 20 of the base by leads 4 and 15 and 45 leads 18 and 16 respectively. The auxiliary filament 24 is thus connected in parallel with both the series filament 6 and the gaseous electric discharge device and the full line voltage is applied thereto.

50 Preferably one half of the line voltage is dissipated in the discharge device and the other half in the series resistance 6. The current consumption of the discharge device and the series filament 6 is the same but the light-output of the discharge device is about two and one-half times that of the incandescent filament. If the discharge device has a light-output of 100 lumens, for example, then the filament 6 has a light-output of 40 lumens. Since the light emitted by 55 the discharge device contains practically no red rays and the light emitted by the filament 6 con-

tains about 25% of red rays, that is, about 10 lumens, then of the 140 lumens emitted by the lamp only 10 lumens, or 7%, is red whereas daylight contains 12 to 15% of red. Preferably the auxiliary filament 24 is so dimensioned that it 5 consumes about half as much current as the circuit consisting of the series filament 6 and the gaseous electric discharge lamp device. The voltage across the filament 24 is twice that across the filament 6 and the filament 24 emits 40 lumens of 10 light, about 10 lumens of such light being red rays. The total light-output of the lamp is thus 180 lumens and contains 20 lumens of red rays which constitute 11% of the total lumen out-put. The light emitted by the lamp is thus a close approximation of daylight and the lamp is useful for illumination purposes generally. It will be understood, that the above figures are used for example only, the actual lumen output of the lamp and its light emitting parts being much 20 higher than that given in the example.

While we have shown and described and have pointed out in the annexed claims certain novel features of the invention, it will be understood that various omissions, substitutions and changes 25 in the forms and details of the device illustrated and in its use and operation may be made by those skilled in the art without departing from the broad spirit and scope of the invention, for example, the bulb 12 consists of matte glass to 30 diffuse the light and avoid glare, when desired.

What we claim as new and desire to secure by Letters Patent of the United States, is:—

1. An electric lamp comprising an hermetically sealed envelope, a gaseous electric discharge lamp 35 device mounted in said envelope, a filament connected in series with said discharge device to serve as a ballast resistance therefor and another filament connected in parallel with said discharge device and said series filament, both of said filaments being mounted in said envelope and external to said discharge device.

2. An electric lamp comprising an hermetically sealed envelope, a gaseous electric discharge lamp device mounted in said envelope, a filament connected in series with said discharge device to 45 serve as a ballast resistance therefor and another filament connected in parallel with said discharge device and said series filament, both of said filaments being mounted in said envelope concentric 50 with and external to said discharge device.

3. An electric lamp comprising an hermetically sealed envelope, a gaseous electric discharge lamp device mounted in said envelope, a filament connected in series with said discharge device to 55 serve as a ballast resistance therefor and another filament connected in parallel with said discharge device and said series filament, both of said filaments being mounted in said envelope and external to said discharge device and means in 60 said envelope to short-circuit part of said series filament during the operation of said lamp device.
